UNITED STATES PATENT OFFICE.

WILLIAM W. WILSON, OF CHICAGO, ILLINOIS, ASSIGNOR, BY MESNE ASSIGNMENTS, TO BURROUGHS ADDING MACHINE COMPANY, OF DETROIT, MICHIGAN, A CORPORATION OF MICHIGAN.

PRINTING-RECORDER FOR CALCULATORS.

1,218,346.

Specification of Letters Patent.

Patented Mar. 6, 1917.

Application filed November 12, 1906. Serial No. 343,024.

To all whom it may concern:

Be it known that I, WILLIAM W. WILSON, a citizen of the United States, residing at Chicago, Illinois, have invented certain new and useful Improvements in Printing-Recorders for Calculators, of which the following is a specification.

This invention relates to improvements in the printing devices of calculating machines 10 wherein a plurality of columns are utilized and has for its object the simplifying of means for controlling a number of columns to be printed with one impression.

In the drawings, Figure 1 illustrates a sectional side elevation of a portion of a calculating machine showing the recording mechanism. Figs. 2 and 3 represent details. Fig. 4 represents a modified form of recording mechanism showing the application of my invention thereto. Figs. 5 and 6 represent details of said modification.

In calculating machines, it is deemed desirable, in making a record of the results when a particular column is to be recorded 20 with a number greater than nought, that the succeeding sections or columns should be printed with a cipher. To effect this result therefore, recording devices are usually so constructed that whenever the device is operated to imprint a figure greater than nought in any particular column, the mechanism controlling the succeeding columns is released automatically. It is sometimes desirable however, to print the figures in several columns simultaneously leaving blank space or spaces between columns, to effect what in the trade is called a splitting of the printing mechanism. It is the purpose therefore of my invention to effect a means 30 whereby the release of the printing device may be controlled absolutely as to the number and position of the columns to be controlled.

In my invention, I refer particularly to United States Letters Patent Number 505078 issued to W. S. Burroughs for recording device for calculators, etc., September 12, 1893, and United States Letters Patent Number 580863 issued to De Kerniea J. T. Hiett, for calculating machine, April 20, 1897, as representing the class of devices to which my invention is especially applicable, and to these two patents I refer for a complete description of the machines to which my invention refers, many particulars of which do not constitute any part of my invention, and

which are therefore neither illustrated nor described.

Referring first to Figs. 1 to 3, which illustrate the invention adapted to the Burroughs type of adding machine, A. represents the frame of the calculating machine to which my invention is applied. B. represents the frame supporting the particular mechanism to which my invention is adapted. C. represents a shaft upon which the type levers, hereinafter described, are intended to rock. D. represents the platen and E. the sheet of paper upon which the impression of the type is to be made.

1. represents the key-board and 2, 2, 2 represents keys operating the calculating mechanism not herein shown nor described. 4. represents the type carrier and 5. a lever arm integral with said type carrier by which the same is operated. 6. represents the type blocks slidingly attached to the type carrier 4. 7. represents the hammer designed to drive the blocks 6 against the platen B for the purpose of effecting an impression. Of 80 these type carriers 4, and hammers 7, there are as many as there are columns, determined by the calculating power of the machine. They are arranged side by side upon common shafts and bearings. Hammer 7 is engaged with shaft 8 upon which it is intended to rock. It is fitted at its lower rear side with an elongated slot 9. A bell crank lever 10, rocks upon the rod 11 as a fulcrum, and carries near its upper end a stud 12 which engages the slot 9 of the hammer 7. The hammer 7 is driven rearward against the type block 6 by the rearward movement of the lever 10 actuated by the spring 14 attached to the forward end of the lever 10. 90 As a means of holding the lever 7 in a retracted position, a trigger 16 rotating upon the rod 17 is arranged fitted with a notch intended to engage the pointed rearward end 13 of the lever 10, and hold the said lever and hammer in a retracted position.

A pawl 15 fitted upon a rod 33 is intended to engage the trigger 16, and in operation to withdraw the trigger 16 from its engagement with the lever 10, thereby releasing the said lever and the hammer 7 for the rearward movement. The pawl 15 is moved out of contact with the trigger 16 by engagement with the slanting shoulder 18 of the carrier 4. When the carrier 4 however, is raised in operation far enough to bring any digital type to the printing

line; the pawl 15 is not so moved, and by the force of the spring 14, one end of which is attached to said pawl, it is held in contact with the trigger 16. The rod 33 carrying the pawl 15, is attached at its ends to the upper end of the arms 31, which arms 31, are attached midway to the ends of a rocking shaft 32. When, in operation, the arms 31 are rocked upon the shaft 32, the pawls 15 are moved forward, and such of them as remain in contact with the triggers 16 draw them forward around the rod 17 and release the levers 10, as before described. Upon the front lower portion of the triggers 16, are rear shoulders 19. I hinge at 21 on said trigger 16, the dog cup or coupler 20 which is fitted on one side with the stud 22 so positioned as to engage the shoulder 19 of the trigger lying next to the one to which it is attached, *i. e.*, the trigger next leftward as the machine is viewed from the front.

In Fig. 2, the stud 22 which is illustrated, is attached to the trigger which lies in front of the one there shown, and is shown in this illustration in a detached form solely to illustrate its position relative to the shoulder 19 of the trigger here shown.

On the opposite side of the dog 20, another stud 23 is provided which engages the front edge of the trigger 16 carrying the dog. A third stud 24, is attached to the heel of the dog 20, and is engaged by a forked pawl 25, pivoted on a rod 26, and engaged at its rear end 28, with a key-stem 27. This key-stem extends through slots in key-board 1, and is notched in two or more places at 3, 3 which notches are intended to engage under the key-board. A spring 28, is attached to the bracket 30, fitted upon the arm 29, and also to the key-stem 27 to normally uphold the latter. In operation when the dog 20 rests in its normal position, as shown in Fig. 2, the actuation of any trigger 16, will automatically trip all of the succeeding triggers, *i. e.*, all triggers to the right as the machine is viewed from the front. This succession may be broken at will by thrusting downward a key-stem 27, which movement engages the pawl 25 with the dog 20 and swings the dog upward upon its hinge 21 and out of contact with the shoulder 19, thereby uncoupling that particular trigger from the one *i. e.*, next leftward lying next to it.

It is designed that there shall be a key-stem for each trigger in the machine.

In Figs. 4, 5, and 6, I illustrate a modification of my device adapted to the universal type of adding machine. 7^a designates the hammers of this modification journaled upon the shaft 8^a. The trigger in this modification is a bell crank lever formed of two arms 16^a and 16^b, journaled upon the rod 17^a. The arm 16^b has a shoulder at its free end to engage with the stud 15^a fitted

upon the hammer 7^a. By this engagement, the hammer 7^a is held in a retracted position. When released from this engagement, the hammer 7^a is driven forward by the action of the spring 14^a. In order to effect the release of the hammer 7^a, the arm 16^a is forced forward by suitable mechanism, which operation moves the trigger arm 16^b rearward and free from the stud 15^a. The trigger arm 16^b is held in engagement with the stud 15^a by the action of the spring 34 applied to a downwardly projecting arm of the trigger. 19^a is a stud projecting from one side face of the trigger arm 16^b, and is intended to engage with a suitably designed coupler fitted upon the trigger lying adjacent thereto.

Instead of the dog 20, hereinbefore described, in this modification I provide an engaging face 22^a, which is struck up from a sleeve 20^a which is designed to slide up on the trigger arm 16^b. A stud 24^a is fitted to the shoulder bearing sleeve 20^a, and is designed to engage a slotted pawl or arm 25^a, which is pivoted on a rod 26^a, and at its rear end connected to the key-stem 27^a, which projects above the key-board 1^a, and has adjustable engagement therewith by means of the shoulders 3^a. A spring 28^a connects the key-stem 27^a to the bracket 30^a.

A' represents the outer casing of the machine, and B' represents the frame of the recording device herein described. In operation, when the key-stem 27^a is raised to the position shown in Fig. 4, the shoulder 22^a and the stud 19^a, are disengaged as shown at Fig. 5, as to the triggers 4 and 5 counting from the left. This position effects what is known as a split at the point of the two triggers just named. Upon disengaging the key-stem shoulder 3^a from the keys A', the spring 28^a rocks the lever 25^a and the shoulder 22^a is moved upward into engagement with the stud 19^a, and the co-operation of all the triggers is again effected.

I would not be confined to the particular description herein embodied, my intention being to apply my invention to any and all recording devices of whatsoever construction, wherein the automatic relation between each column to be recorded and each succeeding column is desired and utilized.

What I claim as my invention is:

1. The combination with hammers and independently movable hammer-controlling members of a recording mechanism; of couplers movably mounted on certain of said members respectively for connection with and disconnection from adjacent members, and a manipulating device for each coupler.

2. The combination with hammers and independently movable hammer controlling members of a recording mechanism; of couplers pivotally mounted on certain of said

members respectively for connection with and disconnection from adjacent members, and a manipulative device for each coupler.

3. In recording mechanism, the combination of hammers, independently movable hammer-controlling members, movable couplers normally connecting the members, and a series of independently operable keys and connections for displacing the couplers respectively.

4. The combination with hammers and independently movable hammer-controlling members of a recording mechanism; of couplers movably mounted on certain of said members respectively for connection with and disconnection from adjacent members, and a series of keys and connections for displacing the couplers respectively.

5. The combination with hammers and independently movable hammer-controlling members of a recording mechanism; of couplers pivotally mounted on certain of said members respectively for connection with and disconnection from adjacent members, and a series of keys and connections for displacing the couplers respectively.

6. In recording mechanism, the combination of hammers, independently movable hammer-controlling members, movable couplers normally connecting the members, a series of fingers for displacing the couplers respectively and a series of keys connected to the fingers respectively.

7. The combination with hammers and independently movable hammer-controlling members of a recording mechanism; of couplers movably mounted on certain of said members respectively for connection with and disconnection from adjacent members, a series of fingers for displacing the couplers respectively, and a series of keys connected to the fingers respectively.

8. The combination with hammers and independently movable hammer-controlling members of a recording mechanism; of couplers pivotally mounted on certain of said members respectively for connection with and disconnection from adjacent members, a series of fingers for displacing the couplers respectively, and a series of keys connected to the fingers respectively.

9. In an adding and recording machine, hammers, pawls holding said hammers, devices for releasing said pawls, couplings whereby a pawl in a higher order when released will release the pawls in lower orders, independently operable means for preventing operation of different ones of said couplings, and keys for operating said means, substantially as specified.

10. In a multiple order adding machine, in combination, adding and printing mechanism, automatic cipher-printing mechanism, and optionally operable means whereby the automatic cipher-transfer to the right of an order may be prevented, the printing mechanism including a series of hammers and shiftable hammer-releasing devices, and the optional interrupting of the cipher-transfer being effected through means including a swinging coupler pivotally mounted to swing freely on a pivot-stud fixed on one of said hammer-releasing devices, said coupler being swung by means of a manipulative device individual to it and acting positively to swing and hold it out of coupling position, substantially as specified.

In witness whereof I hereto affix my name in the presence of two subscribing witnesses.

WILLIAM W. WILSON.
